TOASTER END PANEL

Bernard B. Blinstein, Des Plaines, Ill., assignor to
Sunbeam Corporation, Chicago, Ill.

Filed July 8, 1974, Ser. No. 486,787

Term of patent 14 years

Int. Cl. D7—02

U.S. CL. D7—91

FIG. 1 is a front elevational view of a toaster end panel showing my new design;

FIG. 2 is a side elevational view thereof;

FIG. 3 is a top plan view thereof;

FIG. 4 is a bottom plan view thereof;

FIG. 5 is a sectional view taken substantially along the line 5—5 of FIG. 1; and

FIG. 6 is a sectional view taken substantially along the line 6—6 of FIG. 1.

I claim:

The ornamental design for a toaster end panel, as shown.
